UNITED STATES PATENT OFFICE.

JAMES BROWN POTTER, OF NEWPORT, RHODE ISLAND.

FILING-CABINET.

968,977.

Specification of Letters Patent. Patented Aug. 30, 1910.

Application filed January 4, 1910. Serial No. 536,409.

To all whom it may concern:

Be it known that I, JAMES BROWN POTTER, a citizen of the United States, and a resident of Newport, in the county of Newport and 5 State of Rhode Island, have invented a new and Improved Filing-Cabinet, of which the following is a full, clear, and exact description.

Among the principal objects which the 10 present invention has in view are: to provide a filing cabinet wherein the documents filed therein may be closely packed and securely held; to provide filing devices constructed and arranged to conform to the system herein set forth and claimed whereby 15 document filing may be arranged topically; to provide filing devices adapted to be freely and readily removed from the cabinet wherein they are supported, for transportation; to provide a cabinet for transportation 20 of the filing devices, constructed and arranged in trunk form; to provide a trunk-like cabinet for filing devices, constructed and arranged to be used as a temporary 25 desk; and to provide a construction for a cabinet which is durable, economical and efficient.

One embodiment of the present invention is disclosed in the structure illustrated in 30 the accompanying drawings, in which like characters of reference denote corresponding parts in all the views, and in which—

Figure 1 is a perspective view of a trunk-like cabinet constructed and equipped in 35 conformity with the present invention, the view illustrating the cabinet in position for use as a desk; Fig. 2 is a perspective view of an office cabinet constructed and arranged in conformity with the present invention; 40 Fig. 3 is a vertical cross section of the trunk-like cabinet illustrated in Fig. 1, showing the cabinet as closed for transportation; Fig. 4 is a perspective view in detail of one of the flexible filing panels used in conjunction 45 with this invention; Fig. 5 is a perspective view in detail of the skeleton supporting frame for the flexible panels illustrated in Fig. 4, the top of the trunk-like cabinet shown in Fig. 1 being shown in fragmentary 50 form; Fig. 6 is a perspective view in detail of one of the flexible filing panels used in the present invention, shown in folded form for carrying; and Fig. 7 is a perspective view in detail of a document folder or pocket 55 used in conjunction with the present invention.

In the employment of the present invention a system of filing is developed wherein documents are disposed and arranged in compact and portable form. Further, the 60 devices or panels, as they are herein styled, are constructed from variously colored material, the colors being assigned to denote documents of a certain character or relating to a certain topic. In a file so arranged, 65 when constructed in conformity with the present invention, a series of panels are presented to the user, the edge thereof alone showing at the front of the cabinet. The color scheme, however, denotes to the user 70 the location of panels containing the documents of any particular business or relating to any particular topic. While I prefer the color scheme referred to, it will be understood that I do not wish to be confined to 75 the use of panels of varied colors, as the same purpose may be arrived at by tagging the edges of the panels.

The panels employed by me, and as shown in detail in Fig. 4 of the drawings, consist 80 preferably of a flexible cloth hanger, at the upper end of which is threaded a rigid supporting strip 8. The panel body 9 is formed from a single thickness or strip of cloth. Along the vertical edges of the said 85 panel body 9, and on both sides thereof, are sewed or otherwise fixedly secured, narrower strips 10, 10. The strips 10, 10 are fulled and stitched as at the lines 11, 11. The outer edges of the strips are preferably 90 likewise stitched or secured to the outer edges of the body panel 9, thereby forming laterally opening and oppositely disposed pockets. The pockets formed by the strips 10, 10 are separated to form an intervening 95 space, bridged by the documents and the folders 12 thereof. The folders 12 are formed from any suitable stiff, thin paper, folded preferably as shown in Fig. 7 of the drawings, with the two cut edges turned to 100 the central fold of the sheet from which the folder is formed.

When filing documents in the pockets formed by the strips 10, 10, the documents are folded to fit within the folders 12, and 105 the back of the folder is indorsed with the subject matter of the documents contained therein. This indorsement is naturally arranged upon the folder in such manner as to be exposed when the ends of the folder 110 are inserted within the pockets formed by the strips 10, 10, as will be seen by reference

to the drawings in Figs. 3, 4 and 6. In this manner it is obvious that the panel, when thus employed, lends itself readily to the quick inspection by the user of the folder 5 containing the documents desired.

When employing the system herein set forth, and the devices illustrated, the cabinet in which files are kept is provided with a hanger rod 13. Over the hanger rod 13 extends 10 a swivel hook 14 of any suitable construction. The hook 14 is fixedly attached to the strip 8. The panels 9, 9 are suspended upon the rod 13, and extended transversely across the same, nesting in parallel 15 relation each to the other, as shown in Figs. 1 and 2 of the drawings. When in use, however, the assembled panels yield sufficiently to permit the separation at any point into two sections sufficiently removed to permit 20 the strip 8 and panel body connected therewith to be turned parallel to the said rod and facing the outside of the cabinet. It will be understood that the panel may be rotated so that either side may be exposed 25 to view. This arrangement affords ready and easy facility to the user for a more careful survey of the contents of the particular panel which he may desire to withdraw from the cabinet, or from which he 30 may desire to extract the particular document folder 12.

The rod 13 may be a permanent fixture within a permanent cabinet, such as shown in Fig. 2 of the drawings. The panels, and 35 method of arrangement thereof, adapt themselves readily to transportation in compact space. To carry a series of panels of the nature described, and to form a traveling filing cabinet, I have constructed a light 40 skeleton frame 15, as illustrated in Figs. 1 and 5 particularly. Between top cross bars 16, 16 of the said skeleton frame is suspended the rod 13. The cross bars 16, 16 are maintained in their elevated position by 45 uprights 17, 17, which, together with the cross framing illustrated in the drawings are joined to bottom frames 18, 18. The rectangular skeleton frame is cross braced by a diagonal strip 19. The frame is constructed from any form of light, thin and 50 stout material. When carried in the trunk-like cabinet 20 the said frame fills the entire interior when the end 21 and the lid sections 22 and 23 are closed. When the lid sections 55 are closed the cabinet in all respects resembles a trunk of the form and style known as steamer trunks. While these cabinets may be made of various sizes, that preferred by me is of the size usual in steamer trunks, so 60 that the same may be carried in a steamer, and there used when and as desired.

In use, and when contained in the cabinet 20, the frame 15 and documents carried thereby are elevated to the position shown in 65 Fig. 1 of the drawings, wherein the upward

extension raises the frame 15 a little less than one half of its length extended from the cabinet body. To accomplish this the end 21 is thrown back, as illustrated in Fig. 1, and a strap 24 is drawn taut over rollers 70 25 formed in cross bars 26, 26 of the bottom frame 18. The strap 24 is fixedly secured to the body of the cabinet 20, as seen at 27 in Fig. 5 of the drawings. On the opposite panel of the cabinet 20 is a sunken button 75 buckle or device similar to that shown at 27 over which eyelets 28 of the strap 24 are threaded. By means of this arrangement it is obvious that the frame 15 may be extended from the cabinet to any reasonable degree. Further, it will be seen that, although 80 the cabinet may be heavy, the purchase thus obtained permits the easy and ready elevation of the frame when loaded.

When the cabinet 20 is used in the manner above described, it is often desired that a desk may be used in connection therewith for the examination of papers extracted from the panels and document folders contained therein. It is for this purpose that I 85 have divided the lid of the trunk-like structure into the sections 22 and 23, shown more particularly in Fig. 1 of the drawings. The section 22 is hinged, in the manner illustrated, to the section 23, permitting the same 90 to fall away from the trunk body and to rest upon the knees of a person when seated on the usual stool or chair. No support is shown in the drawings, and none is by me desired, as I prefer that when the cabinet is 100 open and the desk section 22 not required, the same shall drop to the perpendicular position which removes it as an obstruction which it otherwise would prove. However, if it be desired that the lid should be thus 105 supported, the ordinary strap support attached to the side of the trunk-like body carrying the hinges 29, 29 of the section 23 may be secured to the said trunk body and 110 lid section to support the same in its extended position.

When, after use, the trunk body is to be closed, the strap 24 is removed from engagement with the fastening above referred to, and the strap slacked away, permitting the 115 same to run over the rollers 25 on the frame 18 and the skeleton frame 15, to settle to the end of the trunk body or the bottom of the cabinet, as shown in Fig. 1. It will be understood that when the cabinet is completely 120 loaded with documents the weight upon the rod 13 is excessive, and in such position the weight of the panels resting upon the said rod, if the trunk-like cabinet be dropped upon one of the lower corners, is apt to bend 125 or otherwise distort the said rod. It is to support the said rod 13 that I have provided the wooden strip 30. (See Fig. 3 of the drawings.) On the other hand, should the trunk-like body be set upon the opposite end, 130

or that as shown in Fig. 1 as the top of the cabinet, the settling weight of the panels 9, 9 might dislodge the hooks 14, 14 from the rod 13. It is to prevent the disarrangement 5 of the hooks 14, and at the same time to support in its vertical position the strip 30, or similar device, that I have provided the channelled frame 31. The frame 31 is provided with slots 32, 32 which fit over the upper end of the strip 30, or the end thereof having the slot 33, while the side extensions of the channel frame override and hold in position the hooks 14, 14. Thus, when the trunk-like cabinet is being arranged for 10 traveling, the frame 15 is lowered until it rests upon the end of the trunk-like body. The strip 30 is then inserted between the panels 9, 9 and rested upon the trunk body, while the end is bent out of the vertical until 15 it passes under the rod 13 so that the slot 33 may be threaded over the said rod. Thereupon the strip 30 is brought to the vertical position, and it will be found that the bottom of the slot 33 rests snugly under and 20 supports the rod 13. In this position the frame 31 is inserted over the rod 13 and the hooks 14 thereon, the slots 32, 32 being set over the upper edge of the strip 30. When 25 now the frame 31 is closed and the section 22 is folded thereover and locked, the trunk-like cabinet is ready for transportation, without fear of the documents or panels being in 30 a different position at the end of the journey than they are at the start.

35 With a cabinet formed as herein described, and arranged with filing panels systematized as herein set forth, it is obvious that a business man when traveling may at all times have free and ready access to 40 business files which he may desire, or which it may be necessary that he should consult.

The devices and system herein illustrated and described adapt themselves to a manner of use advantageous and desirable. 45 Having arrived at the end of his journey, a man of business desires to remove certain papers for use in consultation. The present or old method would undoubtedly be that he would extract from his papers carried, a 50 number of files or separated papers. After having used the papers and on returning to his hotel or temporary office, this separation from their natural files necessitates refiling. This is obviated in the present instance by 55 the arrangement of the files in the flexible panel illustrated. This panel adapts itself to be folded, as shown in Fig. 6. To each of the panels I attach a tying cord 34, as seen in the said figure. Thus, when the panel is 60 removed from the rod 13 it is only necessary that the cord 34 should be wrapped upon the folded panel and secured in packet form, as seen in Fig. 6. As above stated, the various panels are arranged to receive only 65 the series of documents pertaining to sep-

arate lines or topics of business, therefore the person using the present described system feels assured that the papers that he has in the panel are related only to the business for the moment in hand. Having used the 70 papers at the consultation, they, on being folded, are immediately returned to the pockets. The bundle is then re-formed, and on the person returning to his hotel or temporary office the panel is again hung in its 75 position within the trunk-like cabinet. By this system of handling and carrying papers, it will be found that the traveling man has always an orderly, methodical set of papers to which he has easy access.

Having thus described my invention, what I claim as new and desire to secure by Letters Patent is:—

1. A filing cabinet, comprising a suspension rod mounted in fixed supports; a plurality of flexible hanging panels; a series of supporting devices mounted on said panels to hold folded documents; and a pivotal hanger for each of said panels.

2. A filing cabinet, comprising a suspension rod mounted in fixed supports; a plurality of flexible hanging panels; a series of supporting devices mounted on said panels in horizontally separated arrangement to hold folded documents in horizontal disposition; and a pivotal hanger for each of said panels.

3. A filing cabinet, comprising a suspension rod mounted in fixed supports; a plurality of flexible hanging panels; a series of supporting devices mounted on both sides of said panels in horizontally separated arrangement to hold folded documents in horizontal disposition; and a pivotal hanger for each of said panels.

4. A filing cabinet, comprising a suspension rod mounted in fixed supports; a plurality of flexible hanging panels; a series of pockets formed on the vertical edges of said panels and opening toward the center thereof; and a pivotal hanger for each of said panels.

5. A filing cabinet, comprising a suspension rod mounted in fixed supports; a plurality of flexible hanging panels; a series of pockets formed on the vertical edges of said panels and on both sides thereof, said pockets being arranged in horizontally separated oppositely disposed pairs; and a pivotal hanger for each of said panels.

6. A filing cabinet, comprising a suspension rod mounted in fixed supports; a plurality of flexible hanging panels; a series of supporting devices mounted on said panels to hold folded documents; and a swiveled hook attached to each of said panels to suspend the same and to permit the same to swing on a vertical center.

7. A filing cabinet, comprising a portable trunk-like receptacle; a side opening door

or cover for said receptacle; a suspension rod mounted in fixed supports within said receptacle and disposed in parallel relation with said door; a plurality of flexible hanging panels; a series of supporting devices mounted on said panels to hold folded documents; and a pivotal hanger for each of said panels.

8. A filing cabinet, comprising a portable trunk-like receptacle; an open sided upright supporting frame slidably mounted in said receptacle; an elevator device to raise and hold the said supporting frame in raised position in said receptacle; a suspension rod mounted in fixed supports within said supporting frame; a plurality of flexible hanging panels mounted on said rod; a series of supporting devices mounted on said panels to hold folded documents; and a pivotal hanger for each of said panels.

9. A filing cabinet, comprising a portable trunk-like receptacle; an open sided upright supporting frame slidably mounted in said receptacle; a flexible supporting member for said frame adjustably attached to said receptacle to vary the extension of the said frame in said receptacle; a suspension rod mounted in fixed supports upon said supporting frame; a plurality of flexible hanging panels mounted on said rod; a series of supporting devices mounted on said panels to hold folded documents; and a pivotal hanger for each of said panels.

10. A filing cabinet, comprising a portable trunk-like receptacle having a two-part side opening door or cover, one of said parts being pivoted on the other part to throw out-

ward from the said receptacle to form a shelf; an open sided upright supporting frame slidably mounted in said receptacle; a flexible supporting member for said frame, adjustably attached to said receptacle to vary the extension of the said frame from said receptacle; a suspension rod mounted in fixed supports upon said supporting frame; a plurality of flexible hanging panels mounted upon said rod; a series of supporting devices mounted on said panels to hold folded documents; and a pivotal hanger for each of said panels.

11. A filing cabinet, comprising a portable trunk-like receptacle having a two-part side opening door or cover, one of said parts being pivoted on the other part to throw outward from the said receptacle to form a shelf; a hinged end closure section for said receptacle; an open sided upright supporting frame slidably mounted in said receptacle; a flexible supporting member for said frame, adjustably attached to said receptacle; a suspension rod mounted in fixed supports upon said supporting frame; a plurality of flexible hanging panels mounted on said rod; a series of supporting devices mounted on said panels to hold folded documents; and a pivotal hanger for each of said panels.

In testimony whereof I have signed this specification in the presence of two subscribing witnesses.

JAMES BROWN POTTER.
